UNITED STATES PATENT OFFICE

2,511,594

BARBECUE GRILL

Peter Loffredo, Waukesha, Wis.

Application July 6, 1945, Serial No. 603,559

3 Claims. (Cl. 126—9)

1

My invention refers to barbecue grills, and more particularly to a type of portable outdoor cooking device.

The object of my invention is to provide a barbecue grill that may be assembled quickly, set up to its operating position, and disassembled in a manner to form a compact unit.

Another object of my invention is to so construct the device that all the component parts fold into and against one another to provide a compact assembly for transportation.

Still another object of my invention is to provide a device of the character described that is adjustable to meet varied conditions, and to permit a plurality of operating positions in relation to the fire box and grid.

A still further object of my invention is to construct a fire box in the device in such a manner to provide easy dumping of the fire and hot coal after its use.

It is apparent that the device, as specified, illustrated and claimed herein, provides a very compact, clean, inexpensive grill that may be constructed out of metal that is light in weight, so that it will adapt itself for transportation very easily.

Other and further objects of my invention will become more apparent as the description proceeds when taken in conjunction with the drawings, in which:

Figure 1 is a perspective view of the assembled device ready for use.

Figure 2 is a perspective view of the fire box or fuel basket, showing its component parts and their relation to one another.

Figure 3 is a perspective view of the spit which is designed to comprise adjustable prongs and to be rotatably and horizontally supported above the grid.

Figure 4 is a top view of the device without the fire basket, showing the table plate in an open position.

Figure 5 is a bottom view of the frame with the legs supported therein, and the table top in a folded position.

Figure 6 is a fragmentary view of the method of assembling the legs, which are shown in cross section, to the frame, and

Figure 7 is a bottom view of the entire assembly in a folded position for transportation.

Similar characters of reference indicate corresponding parts throughout the several views, and referring now to the same, the character 10 shows a rectangular frame illustrated as being constructed of angle iron. At the four corners 55

2

of the frame are shown leg supports in the form of sockets arranged to receive the legs shown as 12. These legs are constructed of tubes, but may be angle iron or any other shaped material. Obviously, the supports 11 must correspond with the contour of the shape of the leg. There are clamping screws 13 through the walls of the leg supports. These screws are employed to retain the legs in a rigid position when the device is assembled. A cross member 14, extending within the rectangular frame 10, supports a table plate 15 of sheet metal. This plate 15 is hingedly attached to the cross member 14 at 16.

There is a grid 17 hingedly attached to the frame 10 by means of hinges 18. This grid extends across the top of the frame 10 between one end of the frame and the cross member 14. The front of the frame 10 is provided with a handle, shown at 19, and a grid clip 20 fastened to the frame 10 and employed for retaining the grid in a closed position when in use.

A basket type of fire box, shown as 21, is provided with end plates 22 which are hingedly supported at 23 and a pair of fuel supports 24 are hingedly attached at 25. These fuel supports 24 consist of a plurality of members 26. In my illustration, I show these members 26 as being tubular. However, they may be of solid bars supported by the members 27, or the fuel support 24 may consist of perforated sheets. The object of the fuel support, of course, is to retain the fuel that is being burnt for the use of the device, and the two fuel supports 24, hinged at 25, are held together at their low point by means of an engaging member 28.

Hingedly attached to the end plate assembly 22 are shown vertical adjustment supports 29 which are equipped with handles 30 at their top and are shown hingedly attached at the point 31. These adjustment supports 29 are provided with adjustment grooves 32 and 32' for supporting the basket assembly 21 and the spit assembly, shown as 33. This spit consists of a pair of stationary prongs 34 and a pair of adjustably mounted prongs 35 mounted to a shaft 38, and fastened to the shaft 38 by means of a thumb screw 36. The depending end 37 of the shaft 38 is arranged to rest within one of the grooves or open slots 32 while the bearing 39 on the shaft 38 would fit into any of the grooves 32. The shaft 38 terminates into a crank handle 40, and a clamp 41 is mounted to the shaft 38 for supporting and retaining the spit assembly in a fixed position when the support 41 contacts one of the adjustment sup-

ports 29 and is fastened to the shaft 38 by means of the fastening screws 42.

In Figure 5, I show the frame 10 together with the grid 17 and the table plate 15 folded into a carrying position, and the four legs 12 held in close contact with the frame 10 by means of resilient clamps 43 supported by the bottom face of the angle iron constituting the frame 10. This is shown in detail in Figure 6.

In Figure 7 I show an assembly plate 44, provided with screws 45, which engage threaded apertures 46 at the bottom of the angle iron frame 10. This permits the folded parts to be held in a fixed position for transporting when the plate 44 is fastened by means of the screws 45.

When the entire unit is assembled for operation, the fire box or basket 21 is supported by means of the projecting hinge members 47 which engage the open slots 32' in the members 29. These hinge members 47 are attached to the one end of the frame 10 and the cross bar 14 constituting a part thereof.

The entire device, shown in Figure 7, is assembled for carrying or conveying, and when the plate 44 is taken off by loosening the screws 45, it permits all of the various component parts to be separated. The legs or standards 12 are placed into the sockets or supports 11 and securely fastened by means of the screws 13. The grid 17 rests on top of the frame 10 and the table top 15 rests on the end of the frame 10. When the grid 17 is raised to a vertical position, the fire box assembly 21 is inserted into the frame, the supports 29 being raised vertical and plates 22 being dropped in a vertical position, and fuel support plates 24 being clamped together at their bottom by the engagement means 28. As the assembly 24 is placed in position, the hinge members 47 engage the slots 32' at any pre-determined height and the grid 17 is lowered to a horizontal position and held in that position by means of the clip 20. There being a space between the grid 17 and the end of the frame 10 and the cross section of the frame 14, it permits the members 29 to be moved up or down thereby placing the fire box closer to or away from the grid 17 depending on the type of material being processed. The plurality of open slots 32' engaging the hinge members 47 permit the adjustment of the fire box assembly 21. Similarly, the spit assembly 33 is placed in position whereby the one end 37 enters one of the open slots 32 and the rotary bearing 39 enters another slot 32. The entire spit may be rotated by means of the crank 40 forming a part thereof or, if desired, a power drive, not shown, may be installed onto the shaft 38 and the entire spit revolved by means of the power unit. The prongs 35, being adjustable on the shaft 38, will make it possible to support any type of material, such as a piece of meat, on the spit, and if it is desired to support this meat in a fixed position, the clamp 41 may be arranged to engage one of the supports 29 and fastened by means of the screw 42. This will keep the shaft 38 from revolving.

While I have herein shown a single type of construction, I am fully cognizant of the fact that many changes in the shape and arrangement of the parts may be made, and I reserve the right to make such changes as I deem necessary and convenient without departing from the spirit of my invention or the scope of the appended claims.

Having thus described my invention, what I claim and desire to secure by Letters Patent in the United States is:

1. A device of the character described, comprising a rectangular frame, sockets attached to said frame, a plurality of leg members arranged for engagement with said sockets, a grid hingedly attached at one end to said frame and supported thereby in a horizontal position, a basket type of firebox frame, said firebox frame provided with end plates tapered toward a point near the lower end and side members in the form of grills hingedly supported by said firebox frame and arranged for contact with said end plates and with one another at their extreme lower end, and a pair of vertical members provided with adjustment notches attached to said fire box for contact with said rectangular frame to permit the suspension of said fire box at a pre-determined distance below said grid.
- 10 2. A device as described in claim 1, having a spit horizontally supported in a rotatable manner by the vertical members on the firebox, said spit provided with adjustable prongs for retaining the object being processed.
- 15 3. A device of the character described, comprising a rectangular supporting frame, a grid supported by said rectangular supporting frame, a plurality of vertical legs engaging said rectangular supporting frame and supporting it in a horizontal position, a firebox provided with a rectangular frame, a pair of vertical supports for suspending said fire box from said rectangular supporting frame, said firebox having a pair of triangular end plates tapering at their bottom and attached to said vertical supports, a pair of grills, said grills hingedly supported by said firebox frame, means for retaining the lower depending ends of said grills in contact with one another at their extreme lower end, a pair of inwardly extending hinge members attached to said rectangular supporting frame, a plurality of downwardly extending notches on said firebox supports, said notches disposed for engagement with 40 said extending members on said rectangular supporting frame thereby making it possible to support said firebox and vary the distance between the firebox and the grid.
- 45
